The ornamental design for an apparatus to control fluid flow
through a tube, as shown and described.

DESCRIPTION

FIG. 1 is a front, top, and right side perspective view of the
apparatus to control fluid flow through a tube, showing my
new design;

FIG. 2 is a front side elevational view thereof;

FIG. 3 is a back side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The ornamental design which is claimed is shown in solid
lines in the drawings. The broken lines shown in the figures
represent portions of the apparatus to control fluid flow
through a tube that form no part of the claimed design.
